UNITED STATES PATENT OFFICE

135,682

DESIGN FOR A TEMPERATURE REGULATOR

Walter Hayward Geddes, Dayton, Ohio, assignor
to United Aircraft Products, Inc., Dayton, Ohio,
a corporation of Ohio

Application January 11, 1943, Serial No. 109,227

Term of patent 14 years

To all whom it may concern:

Be it known that I, Walter Hayward Geddes, a citizen of the United States of America, residing at Dayton, in the county of Montgomery and State of Ohio, and whose post-office address is 9 Maple Drive, Dayton, Ohio, have invented a new, original, and ornamental Design for Temperature Regulators, of which the following is a specification, reference being had to the accompanying drawing, forming part thereof.

In the drawing:

Figure 1 is a perspective view of a temperature regulator, showing my new design;

Figure 2 is a side elevation, and

Figure 3 is a front elevation.

The characterizing features of the design consist in the portions shown in full lines in the drawing.

I claim:

The ornamental design for a temperature regulator, as shown and described.

WALTER HAYWARD GEDDES.
